UNITED STATES PATENT OFFICE.

PIETRO CERONE, OF SYRACUSE, NEW YORK, ASSIGNOR TO SAMUEL BONN, OF SYRACUSE,
NEW YORK.

DESIGN FOR A PANEL FOR WOOD FURNITURE.

50,774.

Specification for Design.

Patented May 15, 1917.

Application filed August 9, 1916. Serial No. 114,056. Term of patent 3½ years.

To all whom it may concern:

Be it known that I, PIETRO CERONE, a subject of the King of Italy, residing at 654 Burnet avenue, Syracuse, New York, have invented a new, original, and ornamental Design for Panels for Wood Furniture, of which the following is a description, reference being had to the accompanying drawing, forming a part thereof.

The figure is a face view of portions of opposite ends of a panel for wood furniture showing my new design, the same ornamen-

tal configuration being repeated throughout the body of the panel of any length which would prohibit the showing of a complete panel.

What I claim is:

The ornamental design for a panel for wood furniture as shown.

PIETRO CERONE.
